UNITED STATES PATENT OFFICE.

HELEN M. FLETCHER, OF SAN FRANCISCO, CALIFORNIA.

DESIGN FOR A WHIRLIGIG TOY.

61,154.

Specification for Design.

Patented July 4, 1922.

Application filed December 21, 1921. Serial No. 524,023. Term of patent 3½ years.

To all whom it may concern:

Be it known that I, HELEN M. FLETCHER, a citizen of the United States, residing in the city and county of San Francisco and State of California, have invented a new, original, and ornamental Design for a Whirligig Toy, of which the following is a specification, reference being had to the accompanying drawing, forming part thereof.

Fig. 1 is a side elevation of the whirligig.
Fig. 2 is an edge view of the same.

I claim:

The ornamental design for a whirligig toy, as shown.

HELEN M. FLETCHER.
